UNITED STATES PATENT OFFICE.

CHARLES H. MANN, OF HADDONFIELD, NEW JERSEY, AND CLINTON A. HIGBEE, OF PHILADELPHIA, PENNSYLVANIA; SAID HIGBEE ASSIGNOR TO SAID MANN.

SAFETY-ENVELOP.

SPECIFICATION forming part of Letters Patent No. 674,785, dated May 21, 1901.

Application filed February 27, 1901. Serial No. 49,025. (No model.)

To all whom it may concern:

Be it known that we, CHARLES H. MANN, residing at Haddonfield, in the county of Camden and State of New Jersey, and CLINTON A. HIGBEE, residing at Philadelphia, in the county of Philadelphia and State of Pennsylvania, citizens of the United States, have invented new and useful Improvements in Safety-Envelops, of which the following is a specification.

Our invention relates to safety-envelops, and more particularly to those adapted to be closed through the medium of a seal of wax or like material, and has for its object to provide a structure which when sealed will offer an effectual resistance to any efforts to abstract the contents thereof and will at the same time be so arranged that it will not be possible to open the same without either breaking the seal or tearing the paper. This object we accomplish by first forming the envelop so that a pocket closed on three sides is provided, which may be folded over onto an enlarged front piece formed integral therewith and adapted to cover one entire side of said pocket and to overlap the same on three sides, said overlapping flaps being brought together and sealed by wax or like material in such manner that the design of the seal, as well as portions of each sealed flap, will lie either just flush with or below the surface of the back of the pocket, thus effectually preventing the insertion of a knife-blade or other instrument to lift the design of the seal unbroken.

In the accompanying drawings, illustrating our invention, Figure 1 is a perspective view of an envelop formed in accordance with our invention, the same being shown open or unfolded and ready for the reception of articles to be transported. Fig. 2 is a similar view showing the pocket folded over onto the front piece and the side flaps of the latter also folded into sealing position. Fig. 3 is a similar view showing all the flaps folded and the envelop ready for sealing. Fig. 4 is a similar view showing the envelop sealed and ready for transportation. Fig. 5 is a slightly-enlarged sectional view taken centrally through the envelop when in the position shown in Fig. 1.

Fig. 6 is a similar view when the envelop is in the position shown in Fig. 3, showing the parts closed and ready for sealing. Fig. 7 is a similar view showing the envelop sealed as in Fig. 4. Fig. 8 is a detail perspective view of a recessed disk attached to the inner surface of the back piece of the pocket and registering with an aperture therein and adapted to receive the sealing-wax and the seal. Fig. 9 is a view similar to Fig. 5, illustrating a slightly-modified construction.

Similar numerals of reference denote corresponding parts in the several views.

In the said drawings the reference-numeral 1 denotes the pocket formed in the blank, the same consisting of a back piece and one bottom and two side flaps sealed together, as shown in Fig. 1. Formed integral with said pocket 1 and extending upward from the back piece thereof is the envelop-front 2, the same being of a size to completely cover one side of said pocket when folded thereon and being provided with two substantially V-shaped side flaps 3 and one substantially V-shaped end flap 4, which are adapted to fold over and partially inclose the side of the pocket 1 opposite to the front piece 2 and to have their free ends register with an aperture 5, formed centrally in the back piece of the pocket 1, as clearly shown in Figs. 3, 6, and 7, it being observed that the ends of the side flaps 3 preferably do not quite meet, as seen in Fig. 2, while the end of the end flap 4 has preferably formed therein a notch 6, substantially coextensive in width with the distance between the ends of end flaps 3, all for a purpose hereinafter to be described.

Attached in any suitable manner to the inner side of the back piece of pocket 1 is a disk 7, formed of any suitable material, preferably paper, the same having a central recessed or depressed portion 8 formed or stamped therein, that registers with the aperture 5 in said back piece, said disk thus providing, in conjunction with the aperture 5, a depression in the surface of the back piece of pocket 1, as seen in Figs. 5 and 6, that is overlaid by the ends of flaps 3 and 4 when the envelop is folded, as seen in Figs. 3 and 6.

From the above description the operation

of our improved construction will be understood to be as follows: The parts being in the position shown in Fig. 1, the pocket 1 is ready for the reception of the money or other package to be transported, which being inserted therein said pocket is then folded up onto front piece 2 and the flaps 3 and 4 of the latter then folded over onto the back piece of said pocket in the position shown in Figs. 3 and 6, 5 the ends of said flaps 3 and 4 thus overlying the aperture 5. Now upon applying melted wax or other sealing medium the same will pass through the notch 6 in flap 4 and flow into the depression 8 in disk 7 and around 10 the ends of flaps 3 and 4. A suitable design-seal being now applied to said sealing medium when in its soft state, said seal being a little smaller in area than the aperture 5, the sealing medium, as well as the ends of the flaps 15 3 and 4, may thus be pressed down just flush with or below the surface of the back piece of pocket 1, as clearly seen in Fig. 7.

It will thus be seen that by reason of the peculiar construction of the envelop and 20 through the double folding of the same any abstraction of the contents without breaking the seal or tearing the paper is effectually prevented, while the countersinking of the seal itself flush with or below the surface of 25 the back piece of pocket 1 absolutely prevents the insertion thereunder of a knife-blade or other implement and the consequent lifting of said seal intact, such an attempt inevitably resulting in the breaking of the seal 30 around the edge of the depressed portion thereof without freeing the depressed ends of flaps 3 and 4 lying beneath the design on said seal.

A further advantage obtained by our improved construction is that the seal by being depressed to or below the normal surface of the envelop is protected against accidental damage due to handling, as will be readily understood.

40 45 As a further measure of precaution the edges of flaps 3 and 4 may be gummed in the usual manner, and thus retained closed independently of the seal.

We have illustrated in Fig. 9 a slightly modified construction, a depression 9 being formed by stamping or otherwise in the body of the back piece of pocket 1 itself, thus taking the place of and dispensing with the aperture 5 therein and the supplemental disk 7, 50 55 the sealing medium flowing therein and being stamped in the manner hereinbefore described.

While we have shown and described but one depression for the reception of the sealing medium, it will be understood that we do not limit ourselves to the same, as two or more points of sealing may be employed, the number of depressions being increased and located accordingly.

60 65 If desired, the edge of the depressed portion 8 may be reversely beveled, so that the sealing medium when it fills said depressed

portion will be, as it were, wedged in position, thus offering a further obstacle to its being lifted out.

Having thus described our invention, what we claim as new, and desire to secure by Letters Patent, is—

1. In a safety-envelop, the body portion thereof, and the closing flap or flaps, said body portion having one or more continuous depressions formed therein below the surface thereof of an area sufficient to receive the sealing medium and an impression from a sealing-stamp. 70

2. In a safety-envelop, the body portion thereof, and the closing flap or flaps, said body portion having one or more depressions formed therein below the surface thereof for the reception of the sealing medium and also portions of said flap or flaps. 80

3. A safety-envelop, consisting of a body portion, and a closing flap or flaps, said body portion being provided with one or more depressions therein below the surface thereof for the reception of a sealing medium, and said flap or flaps arranged when folded to partially overlie said depression or depressions so as to be forced flush with or below the surface of the body portion when a seal is applied to the sealing medium. 90

4. In a safety-envelop, the body portion thereof having a depression or depressions formed therein, a closing flap or flaps partially overlying said depression or depressions, and a sealing medium applied to said body portion and flap or flaps at the point or points of depression, said sealing medium and flap or flaps being forced into said depression or depressions flush with or below the surface of the body portion by the application of a sealing stamp or die. 100

5. A safety-envelop, consisting of a pocket or receptacle closed on three sides and having a depression or depressions formed therein, a front piece extending from the open side thereof and adapted to be folded thereon, closing-flaps attached to said front piece and adapted to be folded over the other side of said pocket or receptacle and to partially overlie said depression or depressions therein, and a sealing medium applied to said pocket or receptacle and flap or flaps at the point or points of depression, said sealing medium and flap or flaps being forced into said depression or depressions flush with or below the surface of the pocket or receptacle by the application of a sealing stamp or die. 110

6. A safety-envelop, consisting of a pocket or receptacle closed at three sides and having a depression formed therein, a front piece extending from the open side thereof and adapted to be folded thereon, side-closing flaps attached to said front piece and adapted to be folded over the other side of said pocket or receptacle and to overlie the depression therein, but not to meet, and an end-closing flap also adapted to be folded over said side of the pocket or receptacle and to overlie said de- 120 125 130

pression and also said side flaps, said end flap having a notch or aperture therein adapted to register with said depression, substantially as and for the purpose described.

5 7. In a safety-envelop, the combination with a body portion having an aperture in one side thereof, and a closing flap or flaps adapted, when folded, to partially overlie said aperture, of a disk recessed to provide a depression therein and attached to said body portion at said aperture, the same serving to receive a sealing medium and the overlying por-

tions of the closing-flaps so that they will lie flush with or below the surface of the body portion when pressed therein.

In testimony whereof we have hereunto set our hands in the presence of two subscribing witnesses.
